MACHINE FOR PLACING LINERS IN
CONTAINER CLOSURES

William F. Schmalz, Rockville, Conn., assignor to
Colt's Patent Fire Arms Manufacturing Co.,
Hartford, Conn., a corporation of Connecticut

Application September 10, 1931, Serial No. 562,187

19 Claims. (Cl. 113—80)

A machine embodying the present invention is particularly adapted for the placing of gaskets or liners in closures for bottles or other containers, especially closures which are provided with 5 internal threads for engaging external threads on the bottles or containers. The closures or caps for which the machine is primarily adapted are molded from an artificial resin or other plastic material, but the machine while primarily 10 adapted for use with molded caps is by no means so limited.

The general object of the invention is to provide a machine for the purpose described which is simple and reliable, which is adapted to 15 perform its work rapidly and with a minimum amount of attention from the operator and which completely seats the liners in the caps neatly and uniformly and without injury to the caps or the liners.

20 A more specific object of the invention is to provide a machine of the class described having means for rotating the liner relatively to the cap to effect a more satisfactory engagement.

Other objects of the invention will be apparent 25 from the following specification and claims.

In the accompanying drawings I have shown the embodiment of the invention which I now 30 deem preferable, but it will be understood that the drawings are intended for illustrative purposes only and are not to be construed as defining or limiting the scope of the invention, the claims forming a part of this specification being relied upon for that purpose.

Of the drawings:

35 Fig. 1 is a front view of a machine embodying the invention.

Fig. 2 is a right end view.

Fig. 3 is a plan view.

40 Fig. 4 is a fragmentary vertical sectional view taken along the line 4—4 of Fig. 3.

Fig. 5 is a fragmentary vertical sectional view taken along the line 5—5 of Fig. 3.

45 Fig. 6 is a detailed view on an enlarged scale, showing the spring detents for holding the caps in the liner receiving position.

Fig. 7 includes a plan view and a combined sectional and elevational view of the plunger for placing the liners in the caps.

50 Figs. 8 and 9 are fragmentary views on an enlarged scale, corresponding respectively to Figs. 4 and 5 and showing those parts of the mechanism which are immediately involved in the moving and holding of the caps and in the placing of the liners therein. In these views a cap

with a liner therein is being ejected and a new cap is being moved into position.

Figs. 10 and 11 are views corresponding respectively to Figs. 8 and 9 but showing the cap in liner receiving position and showing the liner 60 engaging plunger in position to move a liner upward into the cap.

Figs. 12 and 13 are views corresponding respectively to Figs. 8 and 9 but showing the liner engaging plunger in its uppermost position with 65 the liner pressed into place in the cap.

Throughout the drawings the caps to be supplied with liners are indicated by the reference character A, and the liners are indicated by the reference character B. The caps A may be of 70 conventional design, but the machine is particularly adapted to place liners in caps of the type disclosed in my patent for Container closure or bottle cap, No. 1,844,442, dated February 9, 1932. Caps of this type have special liner engaging 75 means such as small special screw threads at their upper ends, these threads being indicated at a in Fig. 8.

Referring particularly to Figs. 1, 2 and 3 of the drawings, 1 represents the main frame for 80 the main machine, the said frame having a flat top plate 1^a. There is also provided an extension frame 2 connected with the main frame and adapted to carry a portion of the feed belt and parts associated therewith. This extension 85 frame has a flat top plate 2^a.

Mounted in suitable bearings on the main frame is a main horizontal power shaft 3 extending transversely of the machine. As shown the power shaft 3 is provided with tight and loose 90 belt pulleys 4 and 5 adapted for engagement with a suitable belt not shown. It will be understood that when the belt is on the pulley 4 the power shaft 3 is continuously rotated. The pulleys are shown merely as a representative means 95 for supplying power to the shaft 3, but it will be understood that any other usual or desired means for this purpose may be used.

As a convenient means for moving or feeding the caps A to the operative portion of the machine 100 I prefer to use and have shown a continuously moving endless belt, the effective portion of which is horizontal or substantially so. The belt as an entirety is represented at 6, and it is supported and guided by means of idler pulleys 7, 8 and 9 105 and also passes around a drive pinion 10 on the power shaft 3. The pulley 7 is carried by the main frame 1 and the pulley 8 is carried by the extension frame 2. The idler pulley 9 is movably mounted and is pressed against the belt 110

by means of a weight 11, the belt being thus maintained in proper tension.

With the machine as shown in the drawings it is contemplated that the caps A to be provided with liners are manually fed or pushed onto the belt 6, but it will be understood that any suitable automatic loading mechanism may be provided without in any way departing from the spirit of the present invention. As shown there is provided a loading plate 12 adjacent the left hand portion of the belt 6, this plate being carried at least in part by the top plate 2^a of the extension frame 2. Preferably the rear portion of this loading plate 12 is slightly inclined as shown. It will be understood that in use a supply of caps to be provided with liners is placed on the plate 12, these caps being manually moved or transferred from the plate 12 to the belt 6, care being taken that the caps are placed on the belt in upright position, that is, with the bottom of each cap facing downward.

In order to maintain the caps in a straight row on the belt there are provided suitable guide rails. As shown there are two rails 13 and 14 at the front and shorter rails 15 and 16 at the rear, these rails being carried by the top plates 2^a and 1^a. Preferably the rails 13 and 14 are formed of sheet metal and carry angle bars 17 and 18 which partly overlie the caps to prevent them from being forced upward. The rails 13 and 14 are adjustable transversely of the belt to accommodate caps of different sizes and for the same reason the angle bars 17 and 18 are adjustable vertically. The rails 15 and 16 are adjustable longitudinally for a purpose to be presently described.

At the operative portion of the machine means are provided for successively engaging the caps A as they are fed and for holding them in fixed positions while the liners are being inserted. When the caps are fed by means of a belt such as has been described, it is necessary to transfer the caps successively from the front end of the row of caps on the belt to the predetermined liner receiving position.

Adjacent the belt is a cap supporting means, preferably in the form of a plate 19, having its top surface at the same level as the top surface of the belt 6. The plate 19 has an aperture 20 therein which at the top has approximately the same diameter as the liners which are to be inserted. Preferably the hole is slightly tapered, being larger at the bottom. It will be understood that the plate 19 is detachable, and that the machine may be provided with a series of interchangeable plates having apertures of different sizes corresponding to the sizes of the caps and liners which are to be handled.

It is desirable that the top of the belt be exactly in register with the top of the plate 19. In order to obtain this condition for belts of various thicknesses, I preferably provide an adjustable belt supporting plate 21 immediately adjacent the cap supporting plate 19. The plate 21 is vertically adjustable by means of screws 21^a, 21^b and is clamped in adjusted position by means of screws 21^b.

Overlying the belt 6 is a stop 22 which limits the forward movement of the row of caps on the belt. Movable transversely in suitable guides 23, 23 on the top plate 1^a is a slide carrying a cap engaging finger 24. This finger is adapted to engage the foremost cap on the belt and to transfer it from the belt to the liner receiving position on the plate 19, that is, to a position

on the plate 19 in register with the hole 20. The slide carrying the finger 24 is operated by means of a lever 25 which is pivoted at 25^a to a bracket carried by the main frame 1. A cam 26 on the main power shaft 3 engages a roller on the lever 25 and serves to move the lever 25 in the counter-clockwise direction, and it is returned in the clockwise direction by means of a spring 27. It will be apparent that by means of this cam and lever construction the slide is regularly reciprocated.

The transverse movement of the successive caps from the belt to the liner receiving position is controlled by means of transverse guides 28 and 29. The guide 28 is preferably an integral extension on the stop member 22 and the guide 29 is preferably an integral extension on the guide rail 16. In order to make adjustment for caps of different sizes the stop 22 with the guide 28 thereon is longitudinally adjustable as is also the rail 16 with the guide 29 thereon. In order to limit the transverse movements of the caps and to prevent them from being carried beyond the liner receiving position the two guides 28 and 29 are provided respectively with spring pressed detents 30, 30, which are pivoted to the respective guides at 31, 31. These detents are pressed toward their cap engaging positions by means of springs 32, 32, such movement being limited by means of stop pins 33, 33. The detents serve to momentarily retain the successive caps in their liner receiving positions, but they are nevertheless yieldable to permit one cap to be pushed out by the next following cap as indicated in Fig. 8.

While the spring detents 30, 30 serve to hold the caps approximately in their liner receiving positions it is necessary for the caps to be more accurately located and more securely held than would be possible by means of mere spring detents. I therefore provide above the liner receiving position a vertically movable plunger 34 which is adapted to descend and clamp each successive cap as it reaches the liner receiving position. Preferably in order that the plunger may not only clamp the cap but also accurately locate it the said plunger is provided at the bottom with oppositely inclined cap engaging portions as indicated at 35, 35. For the sake of simplicity of construction the portions 35, 35 may constitute parts of a single concave conical surface. It will be evident that when the plunger engages the cap as indicated in Fig. 10 the cap is accurately located with respect to the hole 20 and is also firmly held in the desired position.

The plunger 34 is carried by a vertically movable head 36 which is secured to the upper end of a vertically movable rod 37. This rod 37 is guided in suitable bearings in a supporting member 38 secured to the top plate 1^a. The rod 37 is vertically reciprocated by means of a connecting rod 39 pivotally connected at its upper end to the rod 38 and carrying at its lower end an eccentric strap 40 which engages an eccentric 41 on the shaft 3. It will be seen that by means of the eccentric and the connecting rod and the other parts described, the plunger 34 is regularly reciprocated. The movement of the plunger is so timed that the plunger engages the cap immediately upon its being moved to the liner receiving position by the finger 24. The plunger 34 is vertically yieldable with respect to the head 36, being movable upward relatively to the head against the resistance of a coil spring 42. It will be apparent that the spring 42 limits the

pressure that may be applied by the plunger to the cap, thus assuring uniform pressure on all caps notwithstanding minor variations in size and therefore preventing breakage.

5 The normal position of the plunger 34 with respect to the head 36 may be changed by means of a nut 43 engaging threads on the upper end of the plunger. It will be understood that this adjustment may be necessary to adapt the machine for handling caps of different heights.

10 Immediately adjacent the hole 20 in the plate 19 there is located a vertical magazine or guide tube 44 adapted for holding and supplying the liners B which are to be placed in the caps. Preferably and as shown the tube 44 is fitted into an opening 45 formed in an extension on the plate 19. The tube 44 is adapted to hold a supply of liners in horizontal positions and the tube is preferably slotted at one side as indicated at 44^a, in order 20 that the operator may observe the quantity of liners in the tube. The liners may be supplied to the tube 44 either by some automatic feeding device or by means of a supply tube such as indicated at 46 in Figs. 1 and 2. The supply tube may 25 be manually filled with liners and then inserted in the top of the main feed tube 44. Each supply tube upon becoming empty is replaced with a filled tube.

30 Formed in the bottom of the plate 19 is a channel 47 which extends from the bottom of the tube 44 to the hole 20. Movable in this channel is a finger 48 which is adapted to engage the lowermost liner in the tube 44 and push it horizontally into the lower part of the hole 20. This action 35 will be apparent from an examination of Figs. 9 and 11. The finger 48 is formed as an extension on a plate 49 which plate is carried by a slide 50 movable in guides 51, 51 on the top plate 1^a. The slide 50 is adapted to be reciprocated by means 40 of a bell-crank 52 pivoted at 53 to a bracket on the main frame 1. The lower arm of the bell-crank 52 carries a roller which engages a cam 54 on the shaft 3. The bell crank is moved in one direction by the cam and in the opposite direction by a 45 spring 55. It will be apparent that by means of the cam and bell crank the slide 50 is regularly reciprocated, carrying with it the finger 48. These parts are so timed that each liner reaches 50 its position in the hole 20 at substantially the same instant that the cap reaches its liner receiving position over the hole 20.

In order that adjustment may be made for liners of different diameters the plate 49 is adjustable on the slide 50, adjustment being effected by 55 releasing the clamping bolt 56 and relatively moving the plate 49 by means of the adjusting screw 57.

60 For moving the successive liners B upward into the respective caps, I provide a vertically movable plunger 58. This plunger is guided at its upper end by means of a plate 59 located immediately below the plate 19. The movement of the plunger is so timed that it engages the liner as soon as the liner reaches the position shown in Figs. 10 and 65 11, the plunger thereupon moving the liner upward into the cap as shown in Figs. 12 and 13. If the liner should be inaccurately positioned by the finger 49 it will nevertheless be accurately centered by the tapered walls of the hole 20.

70 If the caps to be supplied with liners are of conventional design the plunger 58 may have a simple reciprocatory motion serving merely to push the liner straight upward into the caps. However it is one of the purposes of the present 75 invention to place liners in caps of the type dis-

closed in my aforesaid pending application. When liner retaining threads *a* are provided it is necessary for the liner to be rotated as it is pushed into the cap in order that it may properly engage with and be held by the said threads. In 80 order to thus rotate the liners the plunger 58 is continuously rotated, this plunger by reason of its rotary motion serving to rotate each liner and force it into proper engagement with the special threads *a* in the cap.

85 When the liner is rotated as it is moved upward by the plunger, there is sometimes a tendency for it to be thrown outward by centrifugal force so as to assume an eccentric position. This eccentricity might cause the liner to fail to properly seat itself within the cap. In order to avoid this possibility the plunger 58 may carry a small centrally disposed spring pressed prick point 60 which is shown in detail in Fig. 7. It will be observed that the prick point 60 is carried by a spring pressed plunger 61 and it will be apparent that as the plunger moves upward the prick point 60 will engage the liner and penetrate it sufficiently to prevent it from moving to an eccentric position.

90 The plunger 58 is carried by a rotating spindle 62 which in turn is supported by means of ball bearings 63, 63 in a vertically movable slide 64. The spindle 62 carries a belt pulley 65 which pulley is engaged by a round belt 66. This belt 66 passes over idler pulleys 67, 67 and over a drive pulley 68 on the shaft 3. The plunger 58 is detachable from the spindle 62 and may be replaced by other plungers of different sizes. It will be understood that when the plunger is changed 100 the guide plate 59 is also changed.

105 The slide 64 is guided in a suitable bearing in the supporting member 38. The slide 64 is vertically reciprocated by means of a connecting rod 69 which is pivotally connected with the 115 slide and which at its lower end is provided with an eccentric strap 70 engaging an eccentric 71 on the shaft 3. The connecting rod 69 is preferably adjustable in length by means of an intermediate member 69^a which is provided with right 120 hand and left hand threads as indicated. By adjusting the member 69^a the length of the connecting rod can be changed, thus adjusting the stroke of the plunger so that it will move upward to exactly the proper extent.

125 As the lined caps are successively discharged from the liner receiving position they enter a chute 72 through which they are guided and from which they may discharge into any suitable receptacle such as that shown at C.

130 The operation of the machine will be fully apparent from the foregoing description and only a brief résumé is necessary. The caps A are placed on the belt 6 with their open ends facing downward and are transferred from the belt 135 to the liner receiving position by means of the finger 24. At this liner receiving position they are successively centered and clamped by means of the plunger 34. Simultaneously with the movement of each cap to its liner receiving position a liner B is moved by the finger 48 from the bottom of the tube 44 to a position immediately below the cap. Thereupon the liner is engaged by the rotating plunger 58 and moved upward into the cap, being at the same time rotated so 140 as to properly engage the special threads *a* in the cap. As soon as the plunger 58 is withdrawn from the cap the latter is released by the plunger 34 and is forced out of the liner receiving position by the next following cap as it moves into 145 150

such position. The discharged caps enter the chute 72 and are guided to the receptacle provided for receiving them.

By means of the various adjustments which have been described and by means of the substitution of certain parts the machine can be readily changed to handle caps and liners of various sizes.

What I claim is:

10 1. In a machine for placing liners in closure caps, the combination of means for successively feeding the caps to a predetermined liner receiving position and for successively feeding the liners to a predetermined position in register with the said cap position, means engaging the successive caps for preventing endwise movement thereof, and a rotating plunger movable longitudinally in synchronism with the said cap and liner feeding means for successively engaging the liners to insert them into the respective caps and to rotate them while they are being so inserted.

2. In a machine for placing liners in closure caps, the combination of a supporting plate having an aperture therethrough, mechanism for successively feeding the caps to a liner receiving position with the bottom of each cap adjacent the plate at one side thereof and in register with the aperture therein, mechanism operating in synchronism with the cap feeding mechanism for successively feeding the liners to a position at the opposite side of the plate and in register with the said aperture, and a rotating plunger longitudinally movable in synchronism with the two said feeding mechanisms for engaging the liners successively to simultaneously rotate them and move them through the aperture into the respective caps.

3. In a machine for placing liners in closure caps, the combination of a stationary horizontal supporting plate having a vertical aperture therethrough, mechanism for successively feeding the caps to an upright liner receiving position with the bottom of each cap adjacent the top of the plate and in register with the aperture therein, mechanism operating in synchronism with the cap feeding mechanism for successively feeding the liners to a position at the bottom of the plate and in register with the said aperture, and a vertical rotating plunger longitudinally movable in synchronism with the two said feeding mechanisms for engaging the liners successively to simultaneously rotate them and move them upward through the aperture into the respective caps.

4. In a machine for placing liners in closure caps, the combination of a cap support having a bottom opening therein, mechanism for successively feeding the caps to a liner receiving position on the support with the bottom of each cap adjacent the opening in the support, spring pressed detents additional to the feeding means for engaging each cap at the sides thereof and momentarily holding it in the last said position, and means operating in synchronism with the cap feeding mechanism for successively moving the liners through the said opening in the support into the respective caps.

5. In a machine for placing liners in closure caps, the combination of a supporting plate having an aperture therethrough, mechanism for successively feeding the caps to a liner receiving position with the bottom of each cap adjacent the plate at one side thereof and in register with the aperture therein, a reciprocating plunger addi-

tional to the feeding means for engaging each cap at the top thereof and momentarily clamping it in the last said position, and means operating in synchronism with the cap feeding mechanism and with the clamping plunger for successively moving the liners through the said aperture into the respective caps.

6. In a machine for placing liners in closure caps, the combination of a supporting plate having an aperture therethrough, mechanism for successively feeding the caps to a liner receiving position with the bottom of each cap adjacent the plate at one side thereof and in register with the aperture therein, a reciprocating plunger separate from the feeding means for engaging each cap at the top thereof and momentarily clamping it at the last said position, and a rotating plunger longitudinally movable in synchronism with the cap feeding mechanism and with the clamping plunger for engaging the liners successively to simultaneously rotate them and move them through the said aperture into the respective caps.

7. In a machine for placing liners in closure caps, the combination of a supporting plate having an aperture therethrough and a flat surface surrounding the aperture, mechanism for successively feeding the caps to a liner receiving position with the bottom of each cap adjacent the plate at one side thereof and approximately in register with the aperture therein, a reciprocating plunger additional to the feeding means for engaging each cap and momentarily pressing it against the said flat surface of the plate, the said plunger having oppositely inclined cap engaging portions whereby each cap is accurately registered with the aperture in the plate, and means operating in synchronism with the cap feeding mechanism and with the plunger for successively moving the liners through the said aperture into the respective caps.

8. A machine as set forth in claim 7, wherein the plunger is formed with a recess having a conical surface which engages only the top periphery of the caps so as to accurately register the caps with the aperture in the plate.

9. In a machine for placing liners in closure caps, the combination of a mechanism for successively feeding the caps to an upright liner receiving position, the said mechanism disengaging the caps at the liner receiving position so that each cap as fed by the said mechanism serves to eject the next preceding cap from its said liner receiving position, means additional to the feeding mechanism for engaging each cap to momentarily hold it in its said liner receiving position, and means operating in synchronism with the cap feeding mechanism and with the cap holding means for successively moving the liners vertically upward into the respective caps.

10. In a machine for placing liners in closure caps, the combination of a stationary supporting plate having an aperture therethrough, mechanism for successively feeding the caps to an upright liner receiving position with the bottom of each cap adjacent the said top of the plate and in register with the aperture therein, the said mechanism disengaging the caps at the liner receiving position so that each cap as fed by the said mechanism serves to eject the next preceding cap from its said liner receiving position, means additional to the feeding mechanism for engaging each cap to momentarily hold it in its said liner receiving position, and means operating in synchronism with the cap feeding mech-

- anism and with the cap holding means for successively moving the liners through the said aperture into the respective caps.
11. In a machine for placing liners in closure caps, the combination of a stationary supporting plate having a flat top surface and having an aperture therethrough, mechanism for successively feeding the caps to an upright liner receiving position with the bottom of each cap adjacent the said top surface of the plate and in register with the aperture therein, each cap as fed by the said mechanism serving to eject the next preceding cap from its said liner feeding position, a reciprocating plunger for engaging each cap at the top thereof and momentarily clamping it against the said flat surface of the plate in its said liner feeding position, and means operating in synchronism with the cap feeding mechanism and with the clamping means for successively moving the liners through the said aperture into the respective caps.
12. In a machine for placing liners in closure caps, the combination of a continuously moving substantially horizontal feed belt adapted for carrying a series of caps with their bottoms facing downward, a stop for limiting the movement of the caps in the direction of the belt movement, a transfer slide adjacent the stop for moving successive caps transversely from the belt to a predetermined liner receiving position with their bottoms still facing downward, means for momentarily holding the successive caps in the last said position, and means adjacent the last said position for placing liners in the successive caps.
13. A machine as set forth in claim 12, wherein there are provided guide rails extending longitudinally of the belt and serving to maintain the series of caps in a straight row.
14. In a machine for placing liners in closure caps, the combination of a continuously moving substantially horizontal feed belt adapted for carrying a series of caps with their bottoms facing downward, a stop for limiting the movement of the caps in the direction of the belt movement, a supporting plate adjacent the stop and having an aperture therethrough, a transfer slide for moving successive caps transversely from the belt to a liner receiving position with the bottom of each cap adjacent the top of the plate and in register with the aperture therein, means for engaging each cap and momentarily clamping it in the last said position, and means operating in synchronism with the transfer slide and with the clamping means for successively moving liners through the said aperture into the respective caps.
15. A machine as set forth in claim 14, wherein there is provided a vertically adjustable supporting means for that portion of the belt which is immediately adjacent the plate.
16. In a machine for placing liners in closure caps, the combination of a continuously moving substantially horizontal feed belt adapted for carrying a series of caps with their bottoms facing downward, a stop for limiting the movement of the caps in the direction of the belt movement, a supporting plate adjacent the stop and having an aperture therethrough, a transfer slide for moving successive caps transversely from the belt to a liner receiving position with the bottom of each cap adjacent the top of the plate and in register with the aperture therein, transverse guides between which the caps are moved by the transfer slides, the said guides being adjustable in opposite directions to accommodate caps of different sizes, yieldable fingers carried respectively by the adjustable transverse guides for limiting the last said movement of the successive caps and for approximately locating the caps in the liner receiving position, and means operating in synchronism with the transfer slide for successively moving liners through the said aperture into the respective caps.
17. In a machine for placing liners in closure caps, the combination of a continuously moving substantially horizontal feed belt adapted for carrying a series of caps with their bottoms facing downward, a stop for limiting the movement of the caps in the direction of the belt movement, a supporting plate adjacent the stop and having an aperture therethrough, a transfer slide for moving successive caps transversely from the belt to a liner receiving position with the bottom of each cap adjacent the top of the plate and in register with the aperture therein, yieldable fingers for limiting the last said movement of the successive caps and for approximately locating the caps in the liner receiving position, and means operating in synchronism with the transfer slide for successively moving liners through the said aperture into the respective caps.
18. In a machine for placing liners in closure caps, the combination of a continuously moving substantially horizontal feed belt adapted for carrying a series of caps with their bottoms facing downward, a stop for limiting the movement of the caps in the direction of the belt movement, a supporting plate adjacent the stop and having an aperture therethrough, a transfer slide for moving successive caps transversely from the belt to a liner receiving position with the bottom of each cap adjacent the top of the plate and in register with the aperture therein, transverse guides between which the caps are moved by the transfer slides, the said guides being adjustable in opposite directions to accommodate caps of different sizes, yieldable fingers carried respectively by the adjustable transverse guides for limiting the last said movement of the successive caps and for approximately locating the caps in the liner receiving position, and means operating in synchronism with the transfer slide for successively moving liners through the said aperture into the respective caps.
19. In a machine for placing liners in closure caps, the combination of a continuously moving substantially horizontal feed belt adapted for carrying a series of caps with their bottoms facing downward, a stop for limiting the movement of the caps in the direction of the belt movement, a supporting plate adjacent the stop and having an aperture therethrough, a transfer slide for moving successive caps transversely from the belt to a liner receiving position with the bottom of each cap adjacent the top of the plate and in register with the aperture therein, yieldable fingers for limiting the last said movement of the successive caps and for approximately locating the caps in the liner receiving position, a reciprocating plunger for engaging each cap and momentarily pressing it against the plate, the said plunger having oppositely inclined cap engaging portions whereby each cap is accurately registered with the aperture in the plate, and means operating in synchronism with the cap feeding means and with the plunger for successively moving liners through the said aperture into the respective caps.

WILLIAM F. SCHMALZ.
